UNITED STATES PATENT OFFICE.

CURT WOLF, OF LANGEBRUCK, GERMANY, ASSIGNOR TO GETRIEBEBAU-GESELLSCHAFT
MIT BESCHRÄNKTER HAFTUNG, OF DRESDEN, GERMANY, A CORPORATION OF
GERMANY.

VARIABLE-FEED GEAR.

Application filed January 26, 1926, Serial No 83,902, and in Germany February 10, 1925.

This invention relates to a feed gear having a variable feed stroke and being actuated by pairs of eccentrics formed by members that can be adjusted relatively to each other.

I am aware of the fact that there exist already feed gears having a variable stroke and being operated by eccentrics, the eccentricity of which can be adjusted in order to vary the feed stroke. The individual eccentrics used in connection with said known gears consist of two members that can be adjusted relatively to one another for the purpose of varying the eccentricity. With the constructional forms of said gears that have become known up to now the two members constituting an eccentric are so arranged relatively to each other that at normal running one of said two members is carried round by the other. When these members are to be adjusted relatively to each other in order to change the length of the stroke, the pressure existing between the said two members gives rise to a very great friction whereby the adjustment is rendered difficult.

This drawback is overcome by the present invention, the gist of which resides therein that the two members constituting an eccentric are operated separately. When each of the individual eccentrics is composed of an inner eccentric disk and of an eccentric ring encompassing said disk and being adapted to be turned relatively thereto for the purpose of varying the stroke, it is, by this arrangement, rendered possible to affix the eccentric disks to the driving shaft, whereas the eccentric rings are driven by the same shaft and with the same speed by the intermediary of a suitable separate gearing, for instance a cog-wheel gearing, whereby the arising of friction between the two members of each eccentric is obviated so that they can be adjusted very easily with respect to each other.

My invention is illustrated diagrammatically and by way of example in the accompanying drawing in which Figure 1 is a plan of the device, partly in section, Figure 2 a side view, also partly in section, and Figures 3-5 show several positions of the eccentric disk and the eccentric ring.

On the drawing, 1 denotes a driving shaft, and 2 a bevel-wheel located loosely upon said shaft and provided on its circumferential surface with worm-teeth turning this portion of the bevel-wheel 2 into a

worm-wheel 3. This latter wheel meshes with a worm 4. Affixed to the shaft 1 is a hub 5 from which extend radial pivots 5^a and 5^b carrying loose bevel-wheels 6 and 7 meshing on one side with the bevel-wheel 2 and on the other side with a bevel-wheel 8. As the wheel 3 is prevented from rotation by the worm 4, the wheels 6 and 7 are caused to rotate when being carried round by the members 1, 5, 5^a and 5^b, and the rotary motion is transmitted to the wheel 8, which makes double the number of revolutions of the shaft 1. The wheel 8 sits loosely upon the shaft 1, but is firmly connected with a spur-wheel 9 meshing with a spur-wheel 10 of the same diameter affixed to a shaft 11 extending parallelly to the shaft 1 and serving as countershaft.

I wish it to be understood that the gearing described in the preceding paragraph, except the counter-shaft 11 with its cog-wheel 10, can be replaced by any other suitable gearing, adapted to rotate said wheel 10 and the shaft 11.

This shaft is provided with a plurality of spur-wheels 12, of which there are seven in the constructional form shown by way of example. These wheels mesh with spur wheels 13 located loosely upon the shaft 1 and holding between them eccentric disks 14, of which there are six in the example shown and which are keyed to the shaft 1. These disks are disposed in staggered arrangement around said shaft with respect to their eccentricity, and each is encompassed by, and enclosed in, an eccentric ring 15 having a radial slot 20^a (Figs. 2-5) engaged by a pin 20 supported in the adjacent two cog-wheels 13. Each disk 15 is located in a member 16 provided firstly, with an annular lining 21 which forms the support proper for the appertaining disk 15, and, secondly, with a lateral lug (Fig. 2) by which, and by a pivot 17, it is hinged to a feed and locking gear described in the next paragraph.

In the constructional form of this gear as illustrated by way of example the annular member 16 is connected by the pin 17 with a similar annular member 19 supported rotatably upon balls or rollers 28 carried in recesses 27 provided in the circumferential surface of a disk 26 attached to the shaft 18. When the members 19 are moved in the one direction, also the shaft 18 will be turned, but if said members 19 are turned in the

other direction, they get out of engagement with said shaft 18.

In consequence of the staggered arrangement of the eccentric disks 14 the shaft 18 will be continuously turned in one direction.

For the purpose of changing the direction of rotation of the driven shaft the following arrangement is made.

The shaft 18 carries also a loose cog-wheel 22, as well as a coupling sleeve 24 that can be shifted axially upon said shaft, but rotates with it, and can be coupled alternately with said wheel 22, as well as with another bevel-wheel 25 fixed on a shaft 18^a. The wheels 22 and 25 mesh with a bevel-wheel 23 fixed on a shaft 30. When the sleeve 24 has been shifted to the left so as to get coupled with the wheel 22, the wheel 22 drives the wheel 23 in the one direction, and as the coupling sleeve is rotated by the shaft 18, the rotatory motion will be transmitted by said wheels 22 and 23 to the shaft 30, while the wheel 25 now runs idly. If the sleeve 24 is, however, shifted in the opposite direction the shaft 18 will be coupled with the wheel 25, and the wheel 23 and shaft 30 will be rotated in the opposite direction, while the wheel 22 will now run idly.

The shaft 1 is journaled in the bearings 31 and 32, the shaft 11 in the bearings 33 and 34, the shaft 18 in the bearings 35 and 36 and the shaft 18^a in the one end of the shaft 18 and in the bearing 37 respectively.

Now, the manner of operation of the device is as follows:

Supposing, the shaft 1 be rotated with any definite number of revolutions, the eccentric disks 14 will perform the same number of revolutions. The shaft 11, however, makes double that number of revolutions in that it is turned by the intermediary of the gear members 6, 7, 8, 9 and 10. Of course, also the wheels 12 which are firmly affixed to the shaft 11 are rotated with the same speed. The wheels 13 which are supported loosely upon the shaft 1 have double the circumference of the wheels 12 so that their number of revolutions corresponds to that of the shaft 1, and of the eccentric disks 14. Now, as the eccentric rings 15 are coupled with the wheels 13 by the pins 20, also these rings rotate with the speed of the said disks. The motion of said eccentric members is being communicated to the members 16 which transmit it further to the feed locking gear carried by the shaft 18.

In the position of the parts shown in Figs. 1 and 2 the parts 14 and 15 are so positioned with respect to each other that the eccentricities composed each of one part 14 and one part 15 have no eccentricity, therefore the stroke of the members 16 is zero, that is to say, the shaft 18 is at rest. When, however, the worm 4 is rotated, that motion is transmitted by the members 2, 6, 7, 8, 9, 10, 12,

13 and 20 to the eccentric rings 15 upon the eccentric disks 14 while said disks 14 remain at rest. The pins 20 thereby get shifted in the slots 20^a of said rings and the eccentricity of the eccentrics increases, whereby the members 16 are caused to perform a stroke, in consequence whereof the members 19 are caused to turn forwardly and backwardly. While the first of these movements is going on, the rolls or balls 28 carry the disk 26 round with them in known manner and the shaft 18 is rotated. If the worm 4 is again turned, the eccentric rings 15 are shifted circumferentially further upon the eccentric rings 14 whereby the number of revolutions of the shaft 18 is again changed. It can be changed from zero up to the number of revolutions of the driving shaft 1. The change proceeds in every case perfectly without friction, quickly, and noiselessly.

I claim:

1. A variable feed gear, comprising, in combination, a driving shaft, a driven shaft, eccentrics connected with said driving shaft, adapted to transmit the movement to said driven shaft and composed each of two members, means for shifting said members relatively to one another thereby varying the degree of eccentricity of said eccentrics, and means for driving both members of said eccentrics independently from each other.

2. A variable feed gear, comprising, in combination, a driving shaft, a driven shaft, eccentrics connected with said driving shaft, adapted to transmit the movement to said driven shaft and composed each of an inner eccentric disk and of an outer eccentric ring, means for turning said disks and rings relatively to each other; said disks being firmly secured to said driving shaft, and an intermediate gearing being so arranged and connected with said rings, as to be adapted to rotate these latter with the same number of revolutions as that of said driving shaft.

3. A variable feed gear, comprising, in combination, a driving shaft, a driven shaft, eccentrics connected with said driving shaft, adapted to transmit the movement to said driven shaft and composed each of an inner eccentric disk and of an outer eccentric ring, means for turning said disks and rings relatively to each other; said disks being firmly secured to said driving shaft, cog-wheels located loosely upon said shaft between said rings, pins secured to said wheels parallelly to their axis and engaging radial slots of the said rings, and an intermediate gearing being so arranged and connected with said cog-wheels as to be adapted to rotate these latter with the same number of revolutions and in the same direction as that of said driving shaft.

In testimony whereof I have affixed my signature.

CURT WOLF.
